HULL FOR SHIP CONSTRUCTION

Johannes Kjekstad, Hillside, N. J.

Application February 1, 1930. Serial No. 425,091

6 Claims. (Cl. 114—79)

In order to reduce the weight of the hull for ship construction, for a given carrying capacity, and at the same time provide sufficient strength to adequately resist the forces acting upon a hull 5 when a vessel is propelled through the water, it has been proposed to construct the sides, bottom and deck of the hull from a plurality of members of channel shape in cross section running fore-and-aft and having the flanges of adjacent 10 members abutting and secured together, and it is to such a hull that my invention relates.

Heretofore, in constructing hulls from a plurality of members of channel shape in cross section running fore-and-aft and having their 15 flanges abutting and secured together, the web sections of the members making up the sides, bottom or deck of the hull, have been placed in a common plane. In such constructions, the neutral axis of the built up section forming the deck, 20 side or bottom of the hull is in the same position relative to the extreme fibers of the built up section as the neutral axis of the individual members making up the section. Therefore, the moment of inertia and the section modulus of the 25 members combined in such built up sections remains the same as in the individual member acting alone. Thus, the ability of the members to resist lateral forces acting thereon is the same in the built up section as in the individual members 30 and the moment of inertia of the built up section is increased only in accordance with the increased sectional area.

By my invention, I am enabled to increase the section modulus of the members in the built up 35 section forming the deck, side or bottom, over that of the individual member acting alone, thereby imparting greater strength to the hull or the same strength to a hull constructed from members of less weight. I employ a construction 40 in which the web section of the individual members are offset with respect to the web section of the members secured thereto. In constructing the deck, side or bottom of the hull in this way, the neutral axis of the built up section 45 is shifted so that the moment of inertia of the members of the built up section is greater than the moment of inertia of the individual member acting alone. Consequently, the section modulus of the individual member in the built up section, 50 with respect to the neutral axis of the built up section and the resistance of the member to bending under the action of lateral forces, is increased.

Among the characteristics of my invention, is 55 the fact that I am enabled to avoid "locked in"

stresses in welding the individual members of the hull together.

An important feature of my invention is the fact that all of the joints between the individual members are lap joints and, therefore, may be 60 caulked if desired.

Another advantage of my construction is the fact that the members are secured together in close proximity to the neutral axes where the 65 stresses are nominal.

A further advantage of my construction is the fact that there is ample material for the sides or bottom of the hull to yield without rupturing in case of excessive straining.

Specifically, I employ a construction for hulls 70 for vessels in which the sides and bottom are constructed from a plurality of members of channel shape in cross section running fore-and-aft, having their flanges abutting, and secured together. The individual channel shape members 75 are so arranged that the web sections thereof are reversed with respect to the web sections of the members secured thereto on either side thereof. In arranging the members in this manner, the neutral axis of the built up section is midway 80 of the distance between the planes containing the outer surfaces of two succeeding channel shape members, and the moment of inertia of the members about this neutral axis is greater than the moment of inertia about the neutral axis of the 85 individual member acting alone, thereby increasing the section modulus of the members combined to form the built up sections, and consequently their ability to resist lateral forces.

The deck of the hull is also made up of members 90 of channel shape in cross-section running fore-and-aft with their flanges abutting and secured together. The individual members in the deck are not reversed with respect to each other but are placed in stepped relation progressing from the sides of the hull to the longitudinal center thereof, thereby offsetting the web section of each member with respect to the members secured thereto and shifting the neutral axes of 95 the deck, which increases the section modulus of the combined members and their ability to resist lateral forces. The sides and bottom are secured together by bilge members which are arcuate in cross-section and which may be formed from 100 channel shape members by bending the webs thereof arcuate in cross-section. The hull so formed is strengthened by deck, bottom and side web frame members which are secured together 105 and secured along one edge to the webs of the 110

channel shape members forming the deck, sides and bottom of the hull respectively.

5 Bulkheads may be provided and made similar to the sides and bottom, the channel shaped members running transversely, longitudinally or vertically of the hull. Due to the inherent stiffness of these bulkheads, no additional stiffening means is required. The end of the bulkheads are, of course, secured to the sides, the upper edge 10 to the deck and the lower edge to the bottom of the hull.

15 Other features and advantages of my invention will be apparent from the following particular description of one embodiment thereof taken in connection with the accompanying drawings in which:

Fig. 1 is a plan of a barge embodying my invention;

20 Fig. 2 is a longitudinal central section of the same; and

25 Fig. 3 is an enlarged transverse section thereof, taken on the irregular line 3—3 of Fig. 1.

In the drawings, I have illustrated my invention as applied to the barge which is divided into 25 four compartments in which the cargo is carried. The sides 1, bottom 2, and deck 3 of the hull are formed from a plurality of members of channel shape in cross-section having their flanges 4 abutting and being secured together.

30 The channel shaped members making up the sides and bottom of the hull are reversed with respect to adjacent members. The ends of the flanges 4 of adjacent members overlap. The overlapping portion of the flanges of adjacent 35 channel shaped members abut and are secured together, preferably by welding, although it is obvious that any other suitable securing means may be used. The overlapping of the ends of the flanges 4 of the channel shape members constitute a lap joint, and in being welded together avoid the "locked in" stresses which are incident to the welding of a butt joint. In building up 40 the sections in this manner, that is, by reversing the successive channel shape members, the neutral axes of the built up section lies midway between surfaces of the web sections 5 of succeeding members. The neutral axes of an individual section is in close proximity to the web of the section. Therefore, by reversing succeeding channel 45 shape members in this manner, the neutral axes is shifted so that the moment of inertia of the members combined to form the bottom and sides, is increased, thereby increasing the section modulus of the members and consequently, the ability 50 of the material to withstand lateral forces.

55 The sides and bottom are secured together by bilge members which are shown as channel shape members with the web 6 thereof bent arcuate in cross-section, the flanges 7 of the bilge members 60 being secured to the flanges of the adjacent bottom and side members. At spaced intervals longitudinally of the hull there are provided reinforcing cleats 8 for the bilge members. These cleats are secured at one end to the bilge member 65 and at the other end to the adjacent bottom member.

70 The deck 3 of the barge is also formed from a plurality of channel shape members running fore-and-aft and having their flanges abutting and secured together. The deck members are not, however, reversed with respect to adjacent members, but are stepped progressively from the sides toward the longitudinal center of the hull. This arrangement of the members also shifts the 75 neutral axes of the built up sections so as to

increase the section modulus and the ability of the members in the built up section to resist lateral forces. Furthermore, the offsetting of the webs of the succeeding members of the deck, presents the flanges of the members so as to form a lap joint rather than a butt joint and its consequent advantages in welding the members together.

80 At spaced intervals along the hull, transverse frame members are provided. The transverse frame members consist of side, deck and bottom webs, 9, 10 and 11 respectively, which are secured along one edge to the web sections of the members of the sides, deck and bottom respectively and are secured together at their points of crossing. At the connection between web frame members, there is secured a triangular reinforcing flange 12. Along the inner edge of the web frames, there is secured a reinforcing bar 13.

85 On the deck along the edge of the hatches, 90 there is provided a combing 14 which is also constructed from members of channel shape in cross-section. The combing is supported by brackets 15 secured at one end to the combing and at the other end to the deck 3.

95 The athwartship bulkheads 16, which divide the hull into compartments, are also formed from a plurality of members of channel shape in cross-section, the members running transverse of the hull and being reversed relative to adjacent members. The bulkheads are secured along their upper edge to the deck and at their ends to the sides and along their lower edge to the bottom. Longitudinal bulkheads similarly constructed 100 may also be provided.

105 The curved bow and stern of the hull may be constructed from overlapped steel plates or with channel members bent to the desired form.

110 If desired, bumper rails 17 may be provided and may be secured between the flanges of one or more 115 of the channel shape members forming the sides.

120 In the construction shown in the drawings and described immediately above, the increased ability of the material to withstand lateral forces may be utilized in reducing the weight of the 120 channel shape members of which the hull is constructed and thereby decrease the weight of the hull for a given carrying capacity.

125 The effect of the reversing of the members in the side and bottom is to form substantially corrugated sides and bottom which provides sufficient material to permit the sides or bottom to yield considerably before rupturing when subjected to excessive straining. Furthermore, the 130 reversing of the members forming the bottom results in the formation of a series of parallel keels which materially aid in stabilizing the vessel.

135 It is also to be noted that all of the joints between members in the deck, sides and bottom of the hull are lap joints and may be caulked if desired.

140 It is obvious that various changes may be made in the illustrated embodiment above particularly described within the principle and scope of my invention as expressed in the appended claims.

I claim:

1. In a hull for ship construction, a deck constructed from a plurality of members of channel shape in cross-section running fore-and-aft and having their flanges abutting and secured together, the web section of the channel shaped members being in stepped relation.

145 2. In a hull for ship construction, a deck constructed from a plurality of members of channel shape in cross-section running fore-and-aft and 150

having their flanges abutting and secured together, the web section of the channel shaped members being in stepped relation progressively from the sides to the longitudinal center of the hull.

3. In a hull for ship construction, bottom, deck and sides constructed from a plurality of members of channel shape in cross-section and having their flanges abutting and secured together, the web sections of the channel shaped members forming the deck being in stepped relation, and the web sections of each of the members forming the sides and bottom being reversed with respect to the members secured thereto.

10 4. In a hull for ship construction, bottom, deck, sides and bilge constructed from a plurality of members of channel shape in cross-section and having their flanges abutting and secured together, the web sections of the channel shaped members forming the deck being in stepped relation progressively from the sides to the longitudinal center of the hull, the web sections of each of the side members being reversed with respect to the members secured thereto, and the 20 web section of the bilge member uniting the sides and bottom being bent arcuate in cross-section.

25 5. In a hull for ship construction, bottom, deck, sides and bilge constructed from a plurality of members of channel shape in cross-section and having their flanges abutting and secured together, the web sections of the channel shaped mem-

bers forming the deck being in stepped relation progressively from the sides to the longitudinal center of the hull, the web sections of each of the side members being reversed with respect to the members secured thereto, the web section of the bilge member uniting the sides and bottom being bent arcuate in cross-section, and transverse deck, bottom and side web frame members secured together and along one edge to the web sections of the channel shaped members.

30 6. In a hull for ship construction, bottom, deck, sides and bilge constructed from a plurality of members of channel shape in cross-section and having their flanges abutting and secured together, the web sections of the channel shaped members forming the deck being in stepped relation progressively from the sides to the longitudinal center of the hull, the web sections of each of the side members being reversed with respect to the members secured thereto, the web section of the bilge member uniting the sides and bottom being bent arcuate in cross-section, reinforcing cleats secured at one end to the bilge member adjacent the side of the hull and at the other end to the bottom channel shaped member to which the flange of the bilge member is secured, and transverse deck, bottom and side web frame members secured together and along one edge to the web sections of the channel shaped members.
